United States Patent Office.

RICHARD HUBBARD, OF CADIZ, INDIANA.

Letters Patent No. 69,440, dated October 1, 1867.

IMPROVED WASHING MACHINE.

The Schedule referred to in these Letters Patent and making part of the same.

TO ALL WHOM IT MAY CONCERN:

Be it known that I, RICHARD HUBBARD, of Cadiz, in the county of Henry, and State of Indiana, have invented a new and useful improvement in Washing Machines; and I do hereby declare that the following is a full, clear, and exact description of the same, reference being had to the annexed drawings, making part of this specification, in which—

Figure 1 is a perspective view, and

Figure 2 is a vertical transverse section.

The same letters are employed in both figures for the indication of identical parts.

My invention consists in so arranging a washing machine that the clothes shall be placed between an adjustable grated surface, and held in contact with a revolving cylinder having corrugated rubbing-surfaces by the tension of elastic webbing, and in so constructing the revolving cylinder that the wash water shall be carried over with its revolution and discharged upon the clothes being washed.

The following description will enable one skilled in the art to construct and operate my improved machine.

A is the box for containing the wash water, resting upon legs B. Within the box is an adjustable rubbing-board, C, so hinged to the machine that it may have sufficient oscillation to accommodate the clothes placed between it and the revolving cylinder E. The compression of the adjustable rubbing-board C against the clothes is maintained by the constriction of the elastic webbing D attached thereto, and carried over the cap A' which covers the cylinder. It is formed by two side pieces, connected by bars rounded on the side next the cylinder, to avoid tearing the clothes. The cylinder is hung upon a shaft resting on the box A, and turned by a winch, F, by hand, or with a treadle. In the latter case a fly-wheel must be also hung on the shaft. It is constructed with a series of buckets, E¹, somewhat like those of an over-shot water-wheel, by which, as the cylinder revolves, the wash water is raised over the cylinder and discharged upon the clothes to be washed. The spaces between the buckets E² are corrugated, as shown. By the rapid revolution of the cylinder a stream of water is constantly poured upon the clothes subjected to the action of the corrugated surfaces E² and the adjustable grated wash-board C.

What I claim as my invention, and desire to secure by Letters Patent, is—

1. In combination with a revolving rubbing-cylinder, E, the adjustable wash-board C, and bands of elastic webbing D, arranged to operate substantially as set forth.

2. The revolving cylinder E, when constructed with buckets E¹, and rubbing-surfaces E², substantially as set forth.

In testimony whereof I have signed my name to this specification in the presence of two subscribing witnesses.

Witnesses:

RICHARD HUBBARD.
